WALL LAMP

George Sherry, 18480 Santa Alberta Circle,
Fountain Valley, Calif. 92708

Filed Apr. 16, 1973, Ser. No. 351,514

Term of patent 14 years

Int. Cl. D26—05

U.S. Cl. D48—4 B

Fig. 7.

Fig. 8.

Fig. 9.

Fig. 10.

Fig. 11.

Fig. 12.

FIG. 1 is a front perspective view of a wall lamp showing my design;

FIG. 2 is a right side elevational view thereof and is similar to left side elevational view not illustrated;

FIG. 3 is a rear elevational view thereof;

FIG. 4 is a front elevational view thereof;

FIG. 5 is a bottom plan view thereof;

FIG. 6 is a top plan view thereof;

FIG. 7 is a front perspective view of a second embodiment of a wall lamp showing my design;

FIG. 8 is a right side elevational view thereof and is similar to the left side elevational view which is not illustrated;

FIG. 9 is a rear elevational view thereof;

FIG. 10 is a front elevational view thereof;

FIG. 11 is a bottom plan view thereof; and

FIG. 12 is a top plan view thereof.

I claim:

The ornamental design for a wall lamp, substantially as shown and described.
